UNITED STATES PATENT OFFICE.

HERBERT THEODORE BALLARD, OF NORRISTOWN, PENNSYLVANIA.

APPARATUS FOR DYEING YARN.

Application filed November 5, 1924. Serial No. 747,985.

This invention relates to the subject of dyeing yarn used in knitting operations to give a desired tint or cast to the finished fabric.

5 Heretofore difficulty has been experienced in obtaining the so-called "wool tint" in the finished fabric manufactured from cotton yarn. That has been due not only to the inexperience or lack of care of the dyer but 10 principally to the at random methods employed for accomplishing the desired result. Therefore, it is the purpose of the present invention to correct the faulty methods heretofore employed in dyeing yarn, as well as to 15 simplify the same so that the dyeing of the yarn may be accomplished in a quick and economical manner and by the use of simple and inexpensive appliances. Furthermore, an important and primary object of the invention is entirely to obviate the streaky and 20 non-uniform effects produced from yarn dyed by the old methods, and to substitute therefor a process or method that obtains a uniform dyeing of the yarn on the cone from the 25 outside to its core and at definitely spaced points so that as the yarn is drawn off of the cone or spool the dyed portions thereon will be at approximately uniformly spaced intervals, resulting in a uniform striation in 30 the finished fabric that greatly enhances its appearance.

While the invention necessarily is susceptible of being carried out in different ways without departing from the principle of dyeing involved, a simple and preferred manner of performing the process is illustrated in the accompanying drawings, in which:—

Figure 1 is a side elevation of a cone or spool of yarn showing the ends of the cone 40 of yarn dyed in accordance with the invention.

Fig. 2 is a sectional view illustrating the first step in the process to provide for the saturating of the bottom end of the yarn cone with the measured quantity of the liquid dye.

Fig. 3 is a sectional view illustrating the second step in the process to provide for saturating the top end of the yarn cone with a measured quantity of the liquid die.

Fig. 4 is a graphic illustration of a dyed cone of yarn showing the yarn drawing off, in the usual manner, diagonally therefrom, with the result of pulling off spaced dyed portions from the dyed ends of the yarn cone.

Referring to the simple example of the invention shown in the drawings it will be ob-

served that the same distinguishes from all former methods, and particularly from the method of injecting dye into the cone at random, in the particular of providing for dyeing only the top and bottom ends of the cone 60 of yarn. This is shown in Figs. 1 and 4 of the drawings wherein the reference letter C designates the yarn cone having the yarn winding thereon, as usual, from top to bottom 65 and from bottom to top of the cone, the strand of yarn being designated by the reference letter y. This yarn cone, as shown, is dyed only at its ends designated respectively by the reference numerals 1 and 2, the 70 reference numeral 1 indicating the dyed bottom end portion of the cone and the reference numeral 2 indicating the dyed top end portion of the cone.

To obtain the result of uniformly saturating the bottom and top end portions of the yarn cone with liquid dye, various expedients or appliances may be resorted to. One way of performing the necessary steps of the process is shown in Figs. 2 and 3 of the drawings 80 and referring to Fig. 2 it will be observed that it is preferable, though not necessary, to operate first on the bottom or larger end of the yarn cone and to do that it is only necessary to invert the cone and rest the same on 85 a table T or other suitable support and to place over the bottom end thereof a shallow distributing pan designated by the reference numeral 3. This distributing pan has a short upstanding flange 4 around its periphery 90 and the bottom thereof is pierced with a number of drip holes 5 through which the liquid dye is discharged or directed into the bottom end of the yarn cone. To facilitate the uniform saturation of the bottom end of the 95 yarn cone, with the appliance 3, the latter may conveniently be provided with a centrally located depending pivot projection 6 loosely fitting in the open bottom end of the usual core 7 for the cone or spool, and centrally at its upper side with a handle or knob 8 which is held in the fingers of the operator 100 so that a slow spinning motion may be imparted to the pan or device 3 when the measured quantity of liquid dye (indicated by 105 the dotted line in Fig. 2) is poured into the pan by a measuring dipper or equivalent device 9. When the distributing pan 3 has discharged its liquid content of dye into the bottom end of the yarn cone, after a very 110 short interval the dye soaked bottom end of the cone will be sufficiently dry to permit of

inverting the cone on the table or support to the position shown in Fig. 3, that is, with the top end uppermost.

It will be noted that, as usual, the bottom 5 end of the yarn cone is more or less convexed and the distributing pan or device 3 is preferably of a slightly less diameter than the diameter of the bottom end of the cone to insure proper distribution without running

10 the dye solution over the outside of the cone.

Also, as usual, the top end of the yarn cone is dished somewhat as shown in Fig. 3 with the closed end of the cone core 7 projecting slightly through the center, making a shal-

15 low well into which the measured quantity of liquid dye is poured, the same being con-

fined by a conical well-sleeve 10 which tele-

scopically wedges over the top edge portion of the yarn cone. The dotted line in Fig. 3

20 indicates the level of the dye liquid poured into the sleeve 10 and the absorption of the dye at the top end of the yarn cone is sub-

stantially uniform, in the same manner that the bottom end portion absorbs the dye from

25 the distributor 3. The taper of the well sleeve 10 is on a sharper angle than that of the cone to insure a tight fit at the top of the cone.

With only the ends of the yarn cone dyed it will be apparent, as shown in Fig. 4 that the

30 dyed portions of the strand of yarn are ap-

proximately uniformly spaced apart as well

as of substantially the same extent and shade of color. This is due to the fact that the strand of yarn pulls off the cone diagonally from top to bottom and from bottom to top 35 and picks up its dyed portions only from the ends of the cone, said dyed portions on the strand pulled off of the cone being designated by the reference letter *a* in Fig. 4 of the drawings. 40

From the above it is thought that the invention will be fully understood and also that the same is susceptible of being performed with apparatus of different kinds or without special apparatus, without departing from 45 the spirit or sacrificing any of the advantages of the invention.

I claim:

A device for dyeing yarn on the cone comprising a dye holding and distributing member 50 for containing a measured quantity of dye and which member is adapted to be arranged over and is substantially coextensive in area with an end of the cone, said dye holding and distributing member being provided with means for causing penetration of the dye stuff to a uniform depth in, and over the entire area of, the end of the cone. 55

In testimony whereof I hereunto affix my signature.

HERBERT THEODORE BALLARD.
